CLAIM

The ornamental design for a vehicle side door, as shown and described.

DESCRIPTION

FIG. 1 is a perspective view of the vehicle side door (the vehicle side door of the figures being situated on the leftside of a vehicle; the rightside vehicle side door being a mirror image of this leftside vehicle side door and is not shown); FIG. 2 is a front view thereof;

FIG. 3 is a side view thereof; and,

FIG. 4 is a top view thereof.

The broken lines in the drawings illustrate portions of the vehicle side door that form no part of the claimed design.
